WELL CEMENTING DEVICE

Francis Hampton Lee, San Pedro, Calif., assignor
to Baker Oil Tools, Inc., Vernon, Calif., a cor-
poration of California

Application February 24, 1947, Serial No. 730,346

9 Claims. (Cl. 251—8)

1

The present invention relates to well cementing devices, and more particularly to side ported cementing devices adapted to form part of a well casing, liner or similar conduit string.

An object of the present invention is to provide an improved side ported cementing device adapted to form part of a well casing, liner or similar conduit string, which is of compact and comparatively simple construction, maintaining the overall outside diameter of the device to a minimum, the side ports of the device being opened and closed by manipulation of the conduit string.

Another object of the invention is to provide a side ported cementing device adapted to form part of a well casing, liner or similar conduit string, whose side ports can be opened and closed by manipulation of the conduit string, and in which any tendency for the parts to become plugged or fouled is largely, if not entirely, eliminated.

This invention has other objects and aspects which will become apparent from a consideration of the embodiment shown in the drawings accompanying and forming part of the present specification. This form will now be described in detail, but it is to be understood that such detailed description is not to be taken in a limited sense, since the scope of the invention is best defined by the claims appended hereto.

Referring to the drawings:

Fig. 1 is a longitudinal view, partly in elevation and partly in section, of the device, with its parts in their initial positions closing the ports.

Fig. 2 is a partial longitudinal section of the device, with the parts in port opening position.

Fig. 3 is a view similar to Fig. 2, with the parts in position to reclose the ports.

As disclosed in the drawings, the device is in the form of a collar A adapted to constitute part of a string of well casing by being connected to upper and lower casing sections B, C and securing the latter in longitudinal spaced relation. Although specific reference is made in this description to a well casing and casing sections, it is to be understood that the invention is also applicable to liner and similar conduit strings.

The apparatus includes an upper outer tubular member 10 adapted to be threaded onto an upper casing section B, and a lower inner tubular member 11 adapted to be threaded within or onto a lower casing section C. The two members are telescopically arranged with respect to each other, with the lower member 11 disposed within the upper member 10, their interconnection being obtained by straight external threads 12 on the lower member engaging companion straight internal threads 13 on the upper member. The upper member 10 is provided with an

2

upper shoulder or seat 14 positioned above a plurality of circumferentially disposed side ports 15, and the upper end 16 of the lower member constitutes a head adapted to be moved across the ports 15 and into firm sealing engagement with the seat 14, in order to close the ports against passage of fluids in both directions.

A valve sleeve 17 is mounted on the exterior of both the upper and lower members, its upper portion 17a extending initially across the ports 15, there being a suitable seal, such as a round rubber ring 18, mounted in an internal ring groove 19 in the sleeve and adapted to engage the periphery of the upper member 10 above the ports 15, for the purpose of preventing leakage through the ports when the sleeve is disposed thereover. The sleeve 17 is slidably splined to the lower member 11 in any suitable manner, as, for example, by positioning one or more keys 20, welded to the sleeve, within longitudinal slots or key-ways 21 in the lower member. Leakage of fluid between the lower member 11 and sleeve 17 may be prevented by a suitable side seal, in the form of a round rubber ring 22, engaging the inner surface of the sleeve and carried within an external ring groove 23 in the lower member.

The sleeve 17 is secured to the upper member by its internal threads 24 engaging companion external threads 25 on the latter part. These threads 24, 25 are of a different hand from the threads 13, 12 constituting the interconnection between the upper and lower members 10, 11 so that the sleeve 17 and lower member 11 may move relatively in different directions along the upper member 10 upon rotation of the latter. It is to be noted that the threaded connection 24, 25 between the sleeve 17 and upper member 10 extends for a comparatively short distance, to permit the threads to disengage.

In one specific form of the device, the straight threaded connection 13, 12 between the upper and lower members 10, 11 may be constituted by righthand threads, whereas the threaded connection 24, 25 between the sleeve 17 and upper member 10 may be constituted by interengaging lefthand threads, having a lead substantially greater than the lead of the righthand threads. More specifically, the lead of the lefthand threaded connection 24, 25 may be twice the lead of the righthand threaded connection 12, 13, in order that the sleeve 17 may move along the upper member 10 twice the distance that the upper member moves along the lower member 11 upon rotation of the former.

The apparatus is assembled with the upper sleeve seal 18 disposed in sealing engagement with the upper member 10 above the circumferential ports 15, as determined by upward

threading of the sleeve 17 on the upper member 10 and abutting of its shoulder 26 at the lower end of its threaded portion with the lower end 27 of the upper member. The lower member is threadedly secured to the upper member with its head disposed at a substantial distance below the ports. The device, as thus assembled (see Fig. 1), is threaded onto the lower casing section C of the casing string and also onto the upper casing section B, and is lowered with the casing string as a component part thereof in the well bore to the desired depth or location.

In the event cement is to be discharged from the casing string at some point below the collar A, the required amount of cement slurry may be pumped directly into the casing string (preferably preceded by circulating fluid to condition the well bore), passing through the collar device A, whose ports 15 are closed by the sleeve 17, and discharging from the casing string at the specified lower point, as from a casing shoe (not shown), after which the charge of slurry flows upwardly through the annulus around the casing string toward the apparatus A to the desired height.

Following ejection of the lower charge of cement slurry, and after its hardening, the upper portion of the casing string connected to the device A is rotated to the right a predetermined number of revolutions, which threads the upper member 10 downwardly along the lower member 11, and also effects threading of the sleeve 17 downwardly along the upper member 10 and lower member 11, in view of the left-hand threaded connection 24, 25. It is to be noted that the lower charge of cement holds the lower portion of the casing string stationary, which also holds the lower member 11 and the sleeve 17, slidably splined thereto, stationary. Accordingly, rotation of the upper portion of the casing string and the upper tubular member 10 attached thereto effects downward feeding of the upper member 10 along the lower member 11, and of the sleeve 17 down along the upper and lower members 10, 11, in the manner described above.

In the event that the lefthand threaded connection 24, 25 has a lead twice as great as the righthand threaded connection 12, 13, the sleeve 17 moves downwardly along the upper member 10 twice the distance that the upper member 10 is moving downwardly along the lower member 11. Accordingly, the upper end 17a of the sleeve will move down below the ports 15 before the upper head end 16 of the lower member 11 can be positioned across the ports, so that rotation of the upper member 10 a predetermined number of revolutions will completely expose the ports 15 by threading the sleeve 17 downwardly a sufficient distance, but will not, at first, effect closing of the ports by the lower tubular member 11 (see Fig. 2). It is preferred that the lefthand threaded connection 24, 25 become completely disengaged after the sleeve 17 has moved downwardly to port opening position, since the sleeve serves no further port controlling function after it has been moved to port opening position, and there is no need for continuing its downward threading.

A second charge of cement slurry may now be pumped directly into the casing for outward passage through the open ports 15 and for upward flowing through the annulus around the upper portion of the casing string. When suffi-

cient cement slurry has thus been discharged laterally from the collar device A, righthand rotation of the casing string may continue, in order to thread the upper tubular member 10 downwardly over the lower tubular member 11 and bring the seat 14 in the upper member firmly into engagement with the upper head end 16 of the lower member, with the lower member disposed across the ports 15. The lower member 11 may be provided with circular ribs 28 on its head end 16, to provide a multiple metallic seal between the upper and lower members 10, 11, and thus insure against leakage of fluids through the ports 15 upon their engagement.

It is to be noted that the seat 14 on the upper member, engageable with the head end 16 of the lower member, is disposed above the ports 15 and in such position that the lower charge of cement slurry will pass downwardly beyond it without tending to contaminate the seat, in view of its facing in a downward direction. Accordingly, the danger of such seat's becoming contaminated or coated with cement particles is reduced. In any event, should any foreign substances tend to cling to the seat, they will be pierced readily by the ribs 28 on the lower member head 16.

It is further to be noted that the inside diameter of the device is preferably at least equal to and no less than the inside diameter of the casing sections, as B, C, constituting the remaining portion of the casing string itself, to establish no restriction to the passage of cementing plugs and other devices through the collar A. The maximum outside diameter of the device is the diameter of the sleeve valve 17, which is very little more than the outside diameter of the ordinary casing couplings comprising the casing string, thereby enabling the device to be run in well bores whose diameters are not substantially greater than the diameter of the casing sections themselves.

It is, accordingly, apparent that a well cementing device or collar has been provided, in which the ports 15 are closed initially against the passage of fluid to permit fluids to be pumped through the casing string to some lower point, in which the ports are readily opened through rotation of the casing string in one direction, as to the right, and in which the ports are positively reclosed by a continuation of the rotation of the casing string in the same direction, to prevent passage of fluid in both directions through the ports. The device consists of a relatively small number of parts, compactly arranged, and simply constructed.

Having thus described my invention, what I claim and desire to secure by Letters Patent is:

1. Apparatus of the character described, including a first tubular member having a side port, a second tubular member, said members being adapted to form part of a well casing string, a sleeve disposable over said side port to close the same, means providing a slidable spline connection between said second member and sleeve, means providing a first connection between said sleeve and first tubular member, means providing a second connection between said members, said first and second connections being so constructed and arranged that relative rotation between said members moves said sleeve longitudinally of said first member between port closing and port opening positions and moves said members longitudinally of each other between port opening and port closing positions.

2. Apparatus of the character described, in-

cluding a first tubular member having a side port, a second tubular member, said members being adapted to form part of a well casing string, a sleeve disposable over said side port to close the same, means providing a slidable spline connection between said second member and sleeve, means providing a threaded connection between said sleeve and first tubular member, means providing a threaded connection between said members, said threaded connections being so arranged that relative rotation between said members effects movement of said sleeve longitudinally of said first member from port closing to port opening position and moves said members longitudinally of each other to close said port.

3. Apparatus of the character described, including a first tubular member having a side port, a second tubular member, said members being adapted to form part of a well casing string, a sleeve disposable over said side port to close the same, means providing a slidable spline connection between said second member and sleeve, means providing a threaded connection between said sleeve and first tubular member, means providing a threaded connection between said members of a different lead from the lead of said other threaded connection, whereby relative rotation between said members effects longitudinal movement of said sleeve along said first member a different distance than said members are moved longitudinally of each other, to open and close said side port.

4. Apparatus of the character described, including a first tubular member having a side port, a second tubular member, said members being adapted to form part of a well casing string, a sleeve disposable over said side port to close the same, means providing a slidable spline connection between said second member and sleeve, means providing a threaded connection between said sleeve and first tubular member, means providing a threaded connection between said members of a different hand from the hand of said other threaded connection, whereby relative rotation between said members effects movement of said sleeve longitudinally of said first member between port closing and port opening positions and moves said members longitudinally of each other between port opening and port closing positions.

5. Apparatus of the character described, including a first tubular member having a side port, a second tubular member, said members being adapted to form part of a well casing string, a sleeve disposable over said side port to close the same, means providing a slidable spline connection between one of said members and said sleeve, means providing a threaded connection between said sleeve and the other of said members, means providing a threaded connection between said members of a different hand from the hand of said other threaded connection, whereby relative rotation between said members effects movement of said sleeve longitudinally of said first member between port closing and port opening positions and moves said members longitudinally of each other between port opening and port closing positions.

6. Apparatus of the character described, including a first tubular member having a side port, a second tubular member, said members being adapted to form part of a well casing string, a sleeve disposable over said side port to close the same, means providing a slidable spline connection between said second member and sleeve,

means providing a lefthand threaded connection between said sleeve and first tubular member, means providing a righthand threaded connection between said members, whereby relative rotation between said members effects movement of said sleeve longitudinally of said first member between port closing and port opening positions and moves said members longitudinally of each other between port opening and port closing positions.

7. Apparatus of the character described, including a first tubular member having a side port, a second tubular member, said members being adapted to form part of a well casing string, a sleeve disposable over said side port to close the same, means providing a slidable spline connection between said second member and sleeve, means providing a lefthand threaded connection between said sleeve and first tubular member, means providing a righthand threaded connection between said members of a lesser lead from the lead of said lefthand threaded connection, whereby relative rotation between said members effects longitudinal movement of said sleeve along said first member from port closing to port opening position and moves said members longitudinally of each other from port opening to port closing position.

8. Apparatus of the character described, including an upper tubular member having a side port, a lower tubular member, said members being adapted to form part of a well casing string, a sleeve disposable over said side port to close the same, means providing a slidable spline connection between said lower member and sleeve, means providing a lefthand threaded connection between said sleeve and upper tubular member, means providing a righthand threaded connection between said members of a lesser lead from the lead of said lefthand threaded connection, whereby rotation of said upper member effects downward movement of said sleeve to port opening position and moves said upper member down along said lower member to locate said lower member across said port to close the same.

9. Apparatus of the character described, including an upper tubular member having a side port and a valve seat above said port, a lower tubular member disposed within said upper member and having a valve head adapted to engage said seat, said members being adapted to form part of a well casing string, a sleeve on the exterior of said members disposable over said side port to close the same, means providing a slid able spline connection between said lower member and sleeve, means providing a lefthand threaded connection between said sleeve and upper tubular member, means providing a right hand threaded connection between said members of a lesser lead from the lead of said lefthand threaded connection, whereby rotation of said upper member effects downward movement of said sleeve to port opening position and moves said upper member down along said lower member to dispose said port over said lower member and engage its seat with said head.
